(57) **CLAIM**

The ornamental design for a collapsible suspended lighting assembly, as shown and described.

DESCRIPTION

FIG. 1 illustrates a perspective view of an embodiment of the design for the collapsible suspended lighting assembly, wherein parts of the system are shown in broken lines for illustrative purposes;

FIG. 2 illustrates a front view of the embodiment set forth in FIG. 1; and,

FIG. 3 illustrates a side view of the embodiment set forth in FIG. 1.

In this drawing, the solid lines illustrate the claimed ornamental design, whereas the broken lines illustrate environmental features that form no part of the claimed ornamental design of the subject embodiment.

1 Claim, 3 Drawing Sheets
